UNITED STATES PATENT OFFICE.

RALPH FREDERICK DUEL, OF DULUTH, MINNESOTA.

DRAWING-BOARD ATTACHMENT.

1,288,849.

Specification of Letters Patent. Patented Dec. 24, 1918.

Application filed December 15, 1917. Serial No. 207,266.

To all whom it may concern:

Be it known that I, RALPH F. DUEL, a citizen of the United States, and a resident of Duluth, in the county of St. Louis and State of Minnesota, have invented a new and Improved Drawing-Board Attachment, of which the following is a full, clear, and exact description.

This invention relates to drawing boards, and particularly to an attachment therefor, and has for an object the provision of an improved structure which may act in different capacities for causing a comparatively small board to supply the requirements of a larger board.

Another object in view is to provide swinging arms which may be used for supporting articles, and also used for indicating the vanishing point when drawing perspectives or arcs.

A still further object of the invention, more specifically, is the provision of a number of arms in connection with a drawing board, which arms may be rotated substantially in a universal manner, and which carry rotatable extensions acting as stops and as an extended section of the drawing board.

In the accompanying drawing:

Fig. 1 is a perspective view of a drawing board with a plurality of attachments connected therewith disclosing the invention.

Fig. 2 is a longitudinal, vertical, sectional view through Fig. 3 on line 2—2.

Fig. 3 is a bottom plan view of the structure shown in Fig. 2.

Fig. 4 is a transverse sectional view through Fig. 2 on line 4—4.

Referring to the accompanying drawing by numerals, 1 indicates a drawing board of any desired kind, which may be supplied with any desired number of arms 2, said arms being constructed as shown in detail in Figs. 3 and 4, though if desired the outer end may be provided with a tray or rack 3 as shown in Fig. 1 containing tools. The arms 2 may be used as extensions of the board for receiving the compass when striking a large circle, or may be used to place a vanishing point, as well as for other purposes, including supports for books or extra paper 4.

Each of the arms 2 is provided with an apertured end 5 as shown in Figs. 2 and 3 and a ribbed or scored end 6, said ribs or

scores being either radial or parallel as desired. As shown in Fig. 4 end 6 is square and is provided with ridges or teeth 7 on each face, though if desired the end 6 could be made round and the teeth 7 arranged in any desired manner, as for instance longitudinally of the arm 2. The teeth or ridges 7 are intended to engage the teeth 8 on the stationary plate 9, said stationary plate being connected to the board 1 in any suitable manner as for instance by screws 10. This plate is provided with an aperture and a recess in which bracket 11 fits, said bracket having a large annular flange 12 underlying part of the plate 9 as shown in Fig. 2 so that the bracket will freely rotate without being removed. The bracket 11 is provided with an opening 13 through which the end 6 projects and into which the end of the set screw projects for forcing the end 6 of arm 2 against the teeth 8. The use of the teeth 7 and 8 is to positively prevent any radial movement of the arm 2 accidentally and to make it comparatively easy to lock the arm in any desired position.

The outer end of the arm 2 is provided with an apertured portion 5 as above described through which a set screw 15 extends, said set screw fitting into the socket member 16 which is secured to the finger 17 by screws or otherwise as preferred. The finger 17 acts as a part of the board 1 under certain circumstances, as for instance when a perspective is being drawn as shown in Fig. 1, or when a support is desired for a compass. A number of small indentations 18 are provided for receiving the end of the compass or for receiving a pin, or acting in any other desired manner. When drawing a perspective as shown in Fig. 1 a pin may be inserted in any of the sockets 18 and the T-square maintained against the same whereby all the angles of the perspective will be properly positioned. It will be noted that the finger 17 may be rotated around the set screw 15 in a given plane and may be rotated in a plane at right angles to the first mentioned plane upon the rotation of the arm 2, whereby the finger 17 may be placed in any desired position as well as the arm 2.

What I claim is:

1. In a drawing board attachment of the character described, the combination with a board of a plate, means for rigidly securing said plate to a board, a rotatable bracket

mounted on said plate, an arm extending from said bracket, said arm being movable in a plane parallel with the board and also rotatable on its own axis, means for locking said arm in any adjusted position, and an independently rotatable supporting finger on the outer end of said arm.

5 2. An attachment for drawing boards, an arm, means for pivotally mounting the arm

on a drawing board, means for locking the arm in any adjusted position, an independently rotatable finger arranged on the outer end of the arm formed with a plurality of depressions, and means for locking the finger in any desired position in relation to 15 the arm.

RALPH FREDERICK DUEL.
